UNITED STATES PATENT OFFICE.

WILLIAM J. BEST, OF DETROIT, MICHIGAN.

STOVE.

1,366,901.

Specification of Letters Patent.

Patented Feb. 1, 1921.

Application filed July 11, 1918, Serial No. 244,421. Renewed October 8, 1919. Serial No. 329,391.

To all whom it may concern:

Be it known that I, WILLIAM J. BEST, a citizen of the United States, and residing at Detroit, in the county of Wayne and State 5 of Michigan, have invented a new and Improved Stove, of which the following is a specification.

This invention relates to stoves adapted for burning kerosene, gasoline or alcohol, 10 and its object is to provide a structure wherein the burner can be quickly and easily removed and replaced with the least possible work.

This invention consists in the details of 15 construction illustrated in the accompanying drawings and particularly pointed out in the claims.

In the drawing, Figure 1 is a view, partly 20 in section and partly in elevation of a burner embodying the present invention.

Fig. 2 is a plan showing the arrangement 25 of three burners. Fig. 3 is a plan on a reduced scale of the vaporizer used in the burner shown in Fig. 1. Fig. 4 is a similar plan of the burner base.

Similar reference characters refer to like 30 parts throughout the several views.

The burner shown in the drawings embodies a perforated inner chimney 1, a perforated outer chimney 2 and a cowl 3 supported by rods 4 that extend across through the chimneys. The vaporizer preferably 35 consists of an outer side 5 and a trough 6 formed out of the same piece of metal, and an inner side 7 and bottom 8 also pressed up of a single sheet of metal. These two parts of the vaporizer may be welded together so as to render them integral. A wick 9 fits around the inner side 7 of the 40 vaporizer. The edge of the outer side 5 of the vaporizer is preferably formed into a shelf 10 to support the outer chimney 2, while a ring 11 may constitute a bearing member between the side 7 and the inner 45 chimney.

The cup-shaped burner base consists of a bottom 13, a perforated inner cylinder 14, a perforated shelf 15, and an outer cylinder 16. The bottom 13 is provided with an annular bead or rib 17 which rests on the channel bar 18 which constitutes the main cross frame of the stove and on which all the burners are mounted. The channel bar and the bottoms 13 of the base and of the vaporizer are formed with alined holes to receive the bolt 19. The thumb nut 20 on the

upper end of this bolt can be reached by lifting off the cowl and the two chimneys whereupon the remainder of the burner may be removed. The shelf 10 on the outer side 60 5 of the vaporizer has outwardly projecting lugs or fingers 22 which position the vaporizer and chimneys relative to the base. The trough of the vaporizer may be formed with an annular rib 23 to rest on the shelf 65 15. A pipe 24 connects the vaporizer to a source of fuel.

One of the objects desired in the burner embodying the present invention is to keep the vaporizer as hot as possible. The circular ring 14 shown in the drawing spaces the vaporizer from the stationary support 70 18 and prevents, as far as possible, the heat from the vaporizer passing to the stationary support. If the vaporizer were mounted 75 directly on the stationary support there would be a great amount of heat transmitted by the vaporizer to the support, and because of the fact that the stationary support necessarily must be made heavy and large so 80 as to give it sufficient strength to support the three or four burners which are often placed in one stove, and therefore have a large radiating surface, the heat of the vaporizer would be rapidly dissipated.

The details and proportions of the various parts of the burner may all be changed 85 without departing from the spirit of my invention as pointed out in the following claims.

I claim:

1. In a stove, the combination of a support, a cup-shaped burner base mounted thereon, a vaporizer mounted on and extending into said base and comprising perforated co-axial sides and a bottom, concentric chimneys removably mounted on said vaporizer, the support and the bottoms of the base and of the vaporizer being formed with alined holes, and a bolt extending 95 through said holes to secure the vaporizer and base to the support.

2. In a stove, the combination of a channel iron support and a bolt extending upwardly thereon; a base mounted on the support consisting of a circular bottom having a central hole through which the bolt extends, a perforated cylindrical portion extending upwardly from the bottom, an annular shelf at the upper edge thereof and a 100 second cylindrical portion extending upwardly from the outer edge of the shelf; a 110

vaporizer mounted on said base and comprising a perforated bottom having a central hole through which the bolt extends, a trough, and co-axial perforated sides integral with the trough and bottom; inner and outer chimneys supported by the sides of the vaporizer and freely removable therefrom, and a nut on the upper end of the bolt adapted to be screwed down onto the bottom 10 of the vaporizer to hold the vaporizer and base in position.

3. In a stove, the combination of a support having a flat top provided with a hole, a burner base, a vaporizer resting on the 15 burner base, a bottom plate for the vaporizer, said base and plate formed with holes adapted to align with the hole in the support, a bolt extending through said three holes and a nut on the bolt adapted to secure the 20 vaporizer and base to the support, and chimneys extending upward from the vaporizer.

4. In a stove, the combination of a support, a circular intermediate member resting 25 upon the support, a vaporizer mounted on the intermediate member and positioned thereby above the support so as to permit

air to flow between them, a diaphragm extending across the space within the vaporizer not higher than the level thereof, and a bolt extending up from the support to the diaphragm, to secure the several parts in predetermined position.

5. In a stove, the combination of a stationary support, a vaporizer mounted on the support and comprising an annular chamber and a diaphragm, concentric chimneys mounted on the vaporizer above said diaphragm, and a bolt extending through a hole in the support and a hole in said diaphragm to secure the vaporizer in predetermined position on the support.

6. In a stove, the combination of a burner comprising a trough-shaped vaporizer, upwardly extending perforated chimneys and 45 a diaphragm; a stationary support, a cylindrical member resting on said support and upon which said burner is mounted and by which the burner is spaced from the support, and a bolt extending through holes in said 50 support and in said diaphragm to secure the burner to said support.

WILLIAM J. BEST.
